UNITED STATES PATENT OFFICE.

WILSON PINES, OF ROGERS, MICHIGAN.

FINGER FOR GRADERS.

1,290,339.

Specification of Letters Patent.

Patented Jan. 7, 1919.

Application filed August 5, 1918. Serial No. 248,431.

To all whom it may concern:

Be it known that I, WILSON PINES, a citizen of the United States, residing at Rogers, in the county of Presque Isle and State of Michigan, have invented new and useful Improvements in Fingers for Graders, of which the following is a specification.

This invention relates to improvements in graders or screens for stone, ore, coal and 10 like material, such as described in an application filed by me on January 30, 1917, Serial No. 145,469.

The present invention relates to the means for connecting the fingers to the shafts. 15 Another object of the invention is to provide a device of this character which is simple and durable in construction, reliable and efficient in operation and one which can be manufactured and placed upon the market 20 at a minimum cost.

The invention also consists in certain other features of construction and in the combination and arrangement of the several parts, to be hereinafter fully described, illustrated in the accompanying drawings and 25 specifically pointed out in the appended claims.

In describing my invention in detail, reference will be had to the accompanying drawings wherein like characters denote like or 30 corresponding parts throughout the several views, and in which:—

Figure 1 is a partial view of a machine such as described in my former application.

Fig. 2 is an enlarged view of one of the fingers.

Fig. 3 is a section on line 3—3 of Fig. 2.

Fig. 4 is a view of a modification.

As shown in these views, and as described 40 in my former application, the device includes a frame made up of a plurality of spaced bars 1 supported by the legs 2 and having the side pieces 3 and the hopper 4. Transverse shafts 5 pass through the spaced 45 bars 1 and fingers 6 are carried by said shafts and are located in the spaces between said bars.

When the material to be graded is dumped on the hopper 4 and moved downwardly on 50 to the spaced bars it will be acted on by the revolving fingers so that the material will be agitated by said fingers and those pieces which do not pass through the spaces between the bars will be advanced by said 55 fingers to the other end of the machine.

The shafts 5 and the fingers are revolved by means of a chain 7 engaging with the toothed wheels 8 connected with the shafts and suitably driven by any desired means.

As before stated this invention relates to 60 the means of mounting the fingers on the shafts and in carrying out my invention I make said shafts of square formation in cross section and provide each finger with a square recess 9 to receive said shaft. In 65 the form of invention shown in Figs. 2 and 3 the recess 9 is extended as at 9' through the base of the finger and a block 10 fits in the extended part of the recess to hold the shaft in place. This block is held in place 70 by the screws 11 which pass through the edges of the block and the walls of the extended part of the recess as shown.

In the modification shown in Fig. 4 the base of the finger is cut off on a line with 75 the bottom of the recess and a cap 13 is removably secured to this cut off portion by the screws 14.

It will thus be seen that the fingers may be quickly and easily removed and attached 80 to the shafts without necessitating the withdrawal of the shafts from the machine.

It is thought from the foregoing description that the advantages and novel features of my invention will be readily apparent. 85

I desire it to be understood that I may make such changes in the construction and in the combination and arrangement of the several parts, provided that such changes fall within the scope of the appended 90 claims.

What I claim is:—

1. A finger for grading machines comprising an enlarged base having a square recess therein, said recess extending inwardly, 95 from the rear edge of the base and a removable cap closing one end of said recess and forming a continuation of the said edge.

2. A finger for grading machines comprising an enlarged base having a square recess therein, said recess extending inwardly from the rear edge of the base, a block fitting in the end of said recess and closing the same and forming a continuation from said edge and screws engaging the edges of the block and the walls of the recess for holding the block in position. 100 105

In testimony whereof I affix my signature.

WILSON PINES.
